(57) **CLAIM**

The ornamental design for a valve handle, as shown and
described.

DESCRIPTION

FIG. 1 is a perspective view of a valve handle showing the
present invention;

FIG. 2 is a top plan view thereof, and the bottom view is not

illustrated as it forms no part of the present invention;
FIG. 3 is a front elevational view thereof, the rear elevational
view thereof is identical; and,

FIG. 4 is a right side elevational view thereof, the left side

elevational view thereof is identical.
